UNITED STATES PATENT OFFICE

LEWIS CROWFORD ABRAHAM, OF AUDERGHEM, BELGIUM

APPARATUS FOR MANUFACTURING ARTIFICIAL SPONGES

Original application filed October 8, 1930, Serial No. 487,352, and in Belgium October 14, 1929. Divided and this application filed June 16, 1931. Serial No. 544,919.

My present invention relates to artificial sponges for cleaning kitchen-utensils and other similar purposes, according to my co-pending application Serial No. 487,352 of 5 which this application is a division.

According to this co-pending application, said sponges are made of a wire gauze bag containing suitable filling material, the mouth of which is contracted and closed by 10 means of an outer metal cap having its rim provided with teeth bent inwardly through the meshes of said wire gauze.

Now my present invention has for its object an apparatus for closing the mouth of 15 such bags by means of this toothed cap, said apparatus being thus adapted to contract the mouth of the bag, in the shape of a collar, to fit a cap upon said collar and to bend the teeth of the cap inwardly through the meshes 20 of the wire gauze bag.

In the accompanying drawings:

Figs. 1 to 3 are diagrammatical views of different steps of the sponge bag closing 25 operation.

Fig. 4 shows the finished sponge with its closing cap.

Fig. 4a shows a closing cap provided with a handle.

Fig. 5 is a sectional side elevation of a 30 device for making the closure according to my invention.

Fig. 6 is an enlarged horizontal section on line A—B of Fig. 5, showing the parts for drawing the mouth rims of the bag together 35 in two different positions on either side of the line C—D.

Figs. 7 and 8 are a bottom plan view and side elevation respectively of one of the parts for drawing the rims of the mouth together.

The first step consists in drawing the rims of the opening 1 of the sponge shaped wire gauze 2 close together. The metal sponge is formed of a bag-like structure 2 of metal gauze closed at one end 3 and open at the opposite end and containing a suitable filling material. From Figs. 1 and 2 it will be seen how the rims of the opening 1 of said bag may be contracted by means of fingers 4 to form a collar 5.

In the second step a cap 6 provided with a

crown of teeth 7 will be placed upon the collar 5. The teeth 7 will be bent inwardly to cause the same to engage the collar 5 as shown in Fig. 3. To this end I use a plunger 8 which in its upward movement will press the cap 55 6 against the ends of the fingers 4 moved close together, whereby the teeth 7 engaging the curved faces 9 on the fingers 4 will be bent inwardly at right angles to the ring of the cap.

After the cap has been applied as described, the bag material fills out or spreads so that only the rounded part of the cap is visible, as shown more particularly in Figure 4. This rounded part of the cap may provide a convenient surface for a trade-mark or advertisement and forms in effect an ornamental finish to the article.

The cap 6 may also be provided with a handle 6a as shown in Fig. 4a, enabling the sponge to be easily grasped. Said handle 6a 70 may be attached to the cap 6 in any desired way.

The device serving to carry out these steps comprises a frame 10, on which a circular plate 11 having an upstanding rim or flange 75 12 and a central projection 13 is arranged. The flange 12 supports a stationary circular plate 14, the underside of which has a series of radial grooves 15 in which fingers 4 and pushers 16 are alternately arranged, (see Fig. 80 6), which are distinguished over each other in that the fingers 4 are provided with bevelled hooked ends 17, whilst the pushers 16 have not such hooks and are a little shorter than the fingers 4. Each finger and each 85 pusher has its underside provided with a pin 18 engaging one of the oblique curved grooves 19 in a cam disc 20 arranged between the stationary plate 14 and the plate 11. Said cam-disc is adapted to be rotated around the central projection or boss 13 on the plate 11 by means of a handle 21. The pins 18 of a finger 4 and an adjacent pusher 16 engage the same groove 19.

Secured centrally to the plate 11 below the boss 13 is a sleeve 22, which together with a sleeve 23 secured to the frame 10 serves to guide the plunger 8 in the axis of the boss 13 through a central hole 24 in the latter. A lever 25 having a treadle 26 at its lower end, 100

pivoted at 27 on the frame 10 and provided with an eccentric slot 28 engaged by a pin 29 on the plunger 8, serves to move the latter upwardly upon depressing the treadle 26. 5 The treadle lever 25—26 will be moved back to its inoperative position by the action of a spring 30.

Normally the fingers 4 and pushers 16 are in the retracted positions shown on the right hand half of Fig. 6. Upon rotating the cam-disc 20 by means of the handle 21 the oblique curved grooves 19 will act on the pins 18 and cause the fingers 4 and pushers 16 to move towards the centre of the boss 13 as shown 10 on the left hand half of Fig. 6.

In order to close a metallic sponge by means 15 of the apparatus above described, the blank sponge 2 will be placed at the centre of the boss 13, the mouth 1 thereof turned downwardly (Fig. 1), whereupon the cam-disc 20 will be rotated to move the fingers 4 towards each other, whereby the hooked ends of said 20 fingers will engage the meshes of the metal gauze, whilst the pushers 16 will cooperate with said fingers to contract the mouth 1 of 25 the blank and form a collar 5 thereon. Now the treadle 26 will be depressed to move the plunger 8 upwardly, a cap 6 having been placed previously through the opening 31 in the 30 sleeve 22 upon said plunger 8. Thus said cap 6 will be fitted upon the collar 5 and the teeth 7 thereon will be bent inwardly against the curved faces 9 on the fingers 4 as already 35 described whereby the collar 5 will be firmly held in said cap.

Having now fully described my said invention, what I claim and desire to secure by Letters Patent, is:

1. In an apparatus for closing the mouth 40 of a wire gauze bag filled with any desired material by means of a metal cap, the combination of a frame, a stationary horizontal plate on said frame, radial grooves in said plate, fingers having bevelled hooks at one 45 end and pushers guided in said radial grooves, means for moving said fingers and pushers in said grooves, towards the centre of said stationary plate, for the purpose of contracting the mouth of a wire gauze bag placed 50 at the centre of said stationary plate, a vertical plunger arranged centrally to said plate and adapted to receive a metal cap with a toothed pin on its upper end, means for moving said plunger upwardly whereby said cap 55 will be fitted upon the contracted mouth of the wire gauze bag and the teeth thereof bent inwardly against the heads of said fingers and pushers, substantially as set forth.

2. In an apparatus for closing the mouth 60 of a wire gauze bag filled with any desired material for cleaning purposes by means of a metal cap having a toothed rim, the combination of a frame, a lower horizontal plate on said frame, an upper horizontal plate 65 spaced some distance apart from the first

named plate, radial grooves in the lower face of said second plate, fingers having bevelled hooks at one end and pushers guided in said radial grooves, a central boss on the lower plate, a cam-disc arranged on said lower plate and adapted to be rotated around the central boss on said lower plate, curved grooves in said cam-disc, depending pins on said fingers and pushers engaging said curved grooves in said cam-disc, whereby said fingers and pushers will be shifted radially towards the centre of the cam-disc upon the rotation of the latter, means for rotating said cam-disc, for the purpose of contracting the mouth of the bag placed at the centre by the action of said fingers and pushers, a vertical plunger arranged centrally to said plate and cam-disc and adapted to receive a metal closing cap on its upper end, means for moving said plunger upwardly, whereby said cap will be fitted upon the contracted mouth of the wire gauze bag and the teeth thereof bent inwardly against the heads of said fingers and pushers, substantially as set forth. 70 75 80 85

3. In an apparatus for closing the mouth of a wire gauze bag filled with any desired material for cleaning purposes by means of a metal cap having a toothed rim, the combination of a frame, a lower horizontal plate on said frame, an upper horizontal plate 90 spaced some distance apart from the first named plate, radial grooves in the under face of said second plate, long fingers and short pushers arranged alternately in said successive radial grooves for sliding movements therein, bevelled hooked ends with curved under faces on said fingers, a central boss on the lower plate, a cam-disc arranged on said lower plate and adapted to be rotated around the central boss thereon, curved grooves in 95 said cam-disc depending pins on said fingers and pushers, the pins on one finger and the adjacent pusher engaging the same curved groove in said cam-disc, whereby said fingers and pushers will be shifted radially upon the rotation of said cam-disc, means for rotating said cam-disc, for the purpose of contracting the mouth of the bag placed at the centre by the action of said fingers and pushers, a vertical plunger arranged centrally to said plates and cam-disc and adapted to receive a metal closing cap on its upper end, means for moving said plunger upwardly whereby said cap will be fitted upon the contracted mouth of the wire gauze bag and the teeth thereof bent inwardly against the curved undersides of said fingers, substantially as set forth. 100 105 110 115 120

Dated this 1st day of June 1931.

LEWIS CROWFORD ABRAHAM.
